Primary Examiner — Jack Reickel*Assistant Examiner* — Melvin L Davis(74) *Attorney, Agent, or Firm* — Stetina Brunda Garred and Brucker(57) **CLAIM**

The ornamental design for a swim fin, as shown and described.

DESCRIPTION

FIG. 1 is a top perspective view of the swim fin of the present invention showing our new design;
 FIG. 2 is a bottom perspective view thereof;
 FIG. 3 is a top plan view thereof;
 FIG. 4 is a bottom plan view thereof;
 FIG. 5 is right side view thereof;
 FIG. 6 is a left side view thereof;
 FIG. 7 is a front elevational view thereof; and,
 FIG. 8 is a rear elevational view thereof.
